V. E. SISSON,
PRESSED STEEL CAR END,
APPLICATION FILED APR. 17, 1918.

Patented Nov. 11, 1919.

UNITED STATES PATENT OFFICE.

VINTON E. SISSON, OF CHICAGO, ILLINOIS, ASSIGNOR TO WALTER P. MURPHY, OF NEW YORK, N. Y.

PRESSED-STEEL CAR END.

1,321,399.

Specification of Letters Patent. Patented Nov. 11, 1919.

Original application filed June 23, 1913, Serial No. 775,294. Patent No. 1,265,714, dated May 7, 1918.
Divided and this application filed April 17, 1918. Serial No. 229,080.

To all whom it may concern:

Be it known that I, VINTON E. SISSON, a citizen of the United States, residing at Chicago, in the county of Cook and State 5 of Illinois, have invented certain new and useful Improvements in Pressed-Steel Car Ends, of which the following is a specification.

My invention relates to a metal end wall 10 structure for railway cars, more particularly for box cars; and the invention has for one of its objects to provide a new and improved corrugated steel end wall structure for a railway car in which the corrugations extend 15 vertically, or substantially vertically, of the end sheet or sheets, together with certain novel arrangements for anchoring the said sheet metal structure to the car framing whereby the end wall of the car will be capable of resisting cargo thrusts, besides giving 20 rigidity and strength to the whole car body as against the tendency of the car body to "weave".

A further object of the invention is to 25 provide a corrugated end wall for railway cars of double thickness of metal in which the metal sheets are united so that the corrugations form in effect box girders.

The invention consists in the new and improved arrangements, devices and constructions, to be hereinafter described and claimed, for carrying out the above stated objects, and such other incidental objects as will appear from the following description, of certain preferred embodiments of 35 the invention.

This application is a division of my co-pending application, filed June 23, 1913, as Serial No. 775,294 now Patent No. 1,265,714; 40 issued May 7, 1918.

In the drawings—

Figure 1 is a fragmentary end elevation of the body of a box car of wood construction, provided with a sheet steel end wall 45 constructed in accordance with my invention;

Fig. 2 is a vertical section on line 2—2 of Fig. 1; and

Fig. 3 is a fragmentary sectional view taken on line 3—3 of Fig. 1. 50

Like characters of reference designate like parts in the three figures of the drawing.

Referring to the drawing 42 indicates an end sill of the car, 11 the corresponding end plate, 12 the side sills, 13 the side plates, 55 14, 15, side girths, 16 corner posts, and 17 the flooring of the car.

In the preferred form of the invention, the end wall is composed of an upper end sheet 50 and lower end sheets 43—44. The upper sheet is formed with vertical corrugations 20 which terminate within the edges of the sheet and are spaced apart distances equal to their width, so that the corrugated portions of the sheet are divided into sinuous 65 ribs of substantially equal strength and one or both of the lower sheets are formed with similar corrugations 45. By "vertical" as applied to the corrugations, I do not intend to imply that the corrugations need be exactly vertical in a mathematical sense. 70

The upper sheet is secured at its upper edge by bolts 21 to the end plate 11. Its lower edge is overlapped by the upper edges of the lower sheets, and is secured thereto 75 by rivets 48. The sheets are preferably formed with flanges 29 on their vertical edges, which are secured to the corner posts 16. Gusset plates 30 are employed for fastening the upper corners of the upper sheet 80 to the framing of the car, and angular gussets 31 are employed at the lower corners of the lower sheets for attaching the same to the under frame of the car. In addition I employ angular anchoring members 32 85 for securing the end structure at intermediate points to the side girths 14, 15 of the car. The lower edge of the lower sheet 43 is inturned to form a flange 41, which is secured to the end sill 42, the latter being of 90 metal construction.

The lower half of the end structure is reinforced by use of the two sheets 43, 44, which is preferably placed face to face, and secured together. In case both sheets are 95 corrugated, the corrugations of one sheet

aline with those of the other. The sheets are fastened together by rivets 46 along the lines of contact of the sheets between the corrugations and by rivets 47 passing through the lower margin of the sheets and rivets 48 passing through the upper margins of the sheet and through the lower margin 49 of the upper sheet 50.

I claim:

- 10 1. In a railway car, an end wall structure comprising two metal sheets arranged face to face and formed with oppositely projecting alined corrugations, and means for securing said sheets together along contacting lines between said corrugations.
- 15 2. In a railway car, an end wall structure comprising two metal sheets arranged face to face and formed with substantially vertical oppositely projecting alined corrugations, and means for securing said sheets together along contacting lines between said corrugations.
- 20 3. In a railway car, an end wall structure comprising two metal sheets arranged face to face and formed with oppositely projecting alined corrugations which terminate within the edges of the sheet and are spaced apart distances substantially equal to their width, and means for securing said sheets together along contacting lines between said corrugations and along the marginal portions of said sheets beyond the ends of said corrugations.
- 25 4. In a railway car, an end wall structure comprising two metal sheets arranged face to face and formed with substantially vertically oppositely projecting alined corrugations which terminate within the edges of the sheet and are spaced apart distances substantially equal to their width, and means for securing said sheets together along contacting lines between said corrugations and along the marginal portions of said sheets beyond the ends of said corrugations.
- 30 5. In a railway box car, an end wall structure comprising an upper metal end sheet and two metal end sheets extending across the lower portion of the car arranged face to face and formed with oppositely projecting alined corrugations, and means for securing said sheets together along contacting lines between said corrugations and for securing the lower edge of the upper sheet in overlapping arrangement to the upper edges of the other two sheets.
- 35 6. In a railway box car, an end wall structure comprising an upper metal end sheet and two metal end sheets extending across the lower portion of the car arranged face to face and formed with substantially vertical oppositely projecting alined corrugations, and means for securing said sheets together along contacting lines between said corrugations.

corrugations and for securing the lower edge of the upper sheet in overlapping arrangement to the upper edges of the other two sheets.

7. In a railway box car, an end wall structure comprising an upper metal end sheet formed with substantially vertical corrugations and two metal end sheets extending across the lower portion of the car end formed with substantially vertical oppositely projecting alined corrugations, and means for securing said lower sheets together along contacting lines between said corrugations and for securing the lower edge of the upper sheet in overlapped relation to the upper edges of the other two sheets.

8. In a railway car, an end wall structure comprising a metal sheet formed with corrugations which terminate within the edges of the sheet leaving flat margins at opposite ends of the corrugations, and a reinforcing sheet extending across the car from side to side thereof arranged face to face with the other sheet and secured to the same at the margins thereof and along the lines of contact therewith between said corrugations.

9. In a railway car, an end wall structure comprising a metal sheet formed with substantially vertical corrugations which terminate within the edges of the sheet leaving flat margins at opposite ends of the corrugations, and a reinforcing sheet extending across the car from side to side thereof arranged face to face with the other sheet and secured to the same at the margins thereof and along the lines of contact therewith between said corrugations.

10. In a railway box car, an end wall structure comprising an upper metal end sheet, a metal end sheet extending across the lower portion of the car formed with corrugations which terminate within the edges of the sheet leaving flat margins at opposite ends of the corrugations, and a reinforcing sheet arranged face to face with said last named sheet and secured to the same at the margins thereof and along lines of contact therewith between said corrugations.

11. In a railway box car, an end wall structure comprising an upper metal end sheet, a metal end sheet extending across the lower portion of the car formed with substantially vertical corrugations which terminate within the edges of the sheet leaving flat margins at opposite ends of the corrugations, a reinforcing sheet arranged face to face with said last-named sheet, and means for securing said reinforcing sheet to the aforesaid lower sheet between the corrugations thereof and to said upper sheet and the upper flat margin of said lower sheet.

12. In a railway box car, an end wall structure comprising an upper metal end

sheet with substantially vertical corrugations, a metal end sheet extending across the lower portion of the car formed with substantially vertical corrugations which terminate within the edges of the sheet leaving flat margins at opposite ends of the corrugations, a reinforcing sheet arranged face to

face with said last-named sheet, and means for securing said reinforcing sheet to the aforesaid lower sheet between the corrugations thereof and to said upper sheet and the upper flat margin of said lower sheet. 10

VINTON E. SISSON
